COLLAR CONSTRUCTION FOR SHIRTS
 Wilbur S. Gross, 92 Wood Hollow Lane,
 New Rochelle, N.Y.
 Filed Jan. 27, 1961, Ser. No. 85,284
 1 Claim. (Cl. 2—141)

This invention relates to shirt collars of the turned-down type, and particularly to collars of such type which carry means for securing the edges defining a necktie-receiving area in desired position.

Various devices and expedients have heretofore been suggested for coupling together the opposed vertically-disposed forward edges of a turned-down collar whereby the same remains "straight" or "neat." Some of the devices previously suggested take the form of clips and pins which either grasp or penetrate the collar "wings" adjacent the forward edges thereof. These devices, while often neat in appearance, and while detachable from the collar when it is desired to wear the shirt open, are easily lost, and moreover, in many instances permanently mark or damage the collar.

Included among the expedients previously suggested for maintaining shirt collar wings straight, are tabs permanently secured to the underside of the collar adjacent the forward edges thereof and having outer end portions extending into the necktie-receiving area, which outer end portions are adapted to be detachably coupled together. Some expedients of this type are adapted for use with a removable collar-button which can be passed through button holes in the outer end portions of the tabs, while other expedients of this type incorporate cooperating snap fasteners carried on the outer ends of the tabs. Regardless of the exact form which this type of expedient may take, the projecting tabs always extend into the necktie-receiving area, and when the shirt is worn open, the tabs detract from the appearance of the shirt.

Thus, with the prior devices and expedients, one was either faced with the common problem of losing or displacing his collar coupling or maintaining device, or he possessed a shirt which required, for appearance sake, that it always be worn closed and with a necktie.

The present invention has as its primary object the provision of a turned-down shirt collar incorporating means for positively coupling the "wings" of the collar together when the shirt is worn closed, which means are always carried by the shirt collar, and which means can be folded and maintained underneath of the collar when it is desired to wear the shirt with the collar in open position.

More specifically, a primary object of the present invention is to provide on a turned-down-type shirt collar tab means for positively coupling the wings of the collar together when the same is worn closed, which tab means can be folded inwardly beneath the underside of the collar and detachably maintained in folded position so as to remain out of sight when the collar is worn open.

Still further, other, and more specific objects of the present invention are:

(a) To provide on a turned-down shirt collar an improved form of tab coupling means conforming with the preceding objects, which coupling means can be easily manipulated;

(b) To provide such an improvement which is readily adapted for use on conventional shirts;

(c) To provide such an improvement which can be inexpensively manufactured and utilized with existing shirt collar constructions; and

(d) To provide such an improvement which incorporates snap fastener elements for securing the tabs in the respective "open" and "closed" positions.

The invention will be better understood, and objects

2

other than those specifically set forth hereinabove will become apparent, when consideration is given to the following detailed description. Such description refers to the annexed drawings presenting the preferred and illustrative embodiments of the invention. In the drawings,

5 FIGURE 1 is a front perspective view of a shirt provided with a collar constructed in accordance with the instant invention, and presents the collar as it would appear in closed position with the connecting tabs releasably joined together;

10 FIGURE 2 is an enlarged fragmentary front perspective view of the collar wing portions shown in FIGURE 1, FIGURE 2 presenting such portions, and the construction of the connecting tabs, in some detail;

15 FIGURE 3 is an enlarged fragmentary perspective view presenting the collar wing portions in the position shown in FIGURE 2, as the same would appear from the underside of the turned-down collar constructed in accordance with the present invention;

20 FIGURE 4 also is an enlarged fragmentary view, similar to FIGURE 3, but presenting the collar wing portions in open position with the tabs attached thereto folded back beneath the underside of the turned-down collar;

25 FIGURE 5 is a horizontal elevational view of the collar wing portions shown in FIGURE 4, FIGURE 5 presenting in some detail the overlapping relationship of the folded tabs when secured in a position hidden from view, and

30 FIGURE 6 presents fragmental detailed sectional views, taken on the lines *a—a* and *b—b* of FIGURE 3, and showing the preferred disposition of the interlocking cooperating components of fastener elements secured to the collar.

If reference is made to FIGURE 1, it will be noted that the shirt body, presented in phantom, is generally 35 designated by the numeral 2, and that such shirt body is provided with a collar structure generally designated by the numeral 4. The collar structure 4 may be of any conventional design; however, as shown it comprises an inner upstanding collar wall 6 adapted to engage the neck of a wearer, and an outer turned-down portion or collar 8.

The turned-down collar 8, in the closed position, as shown in FIGURE 1, has two ends 10 and 12 disposed in spaced relation to define a necktie-knot-receiving area generally designated by the numeral 14. The end portions or wings of the collar terminate at the ends 10 and 12, and secured to such wings are a pair of tabs 16 and 18 which have overlapping outer end portions projecting beyond the ends 10 and 12 of the collar.

45 50 As best shown in FIGURE 3, the inner end portion of the tab 16, or first tab, is secured to the underside of the collar 8 adjacent the end 12 thereof, and the tab 18, or second tab, has its inner end portion secured to the underside of collar 8 adjacent the end 10 thereof. For purposes of clarity, it should be understood that, in this description, and the annexed claim, the term "inner end portion" refers to those portions of the tabs 16 and 18 which underlie the collar 8, whereas the term "outer end portion" refers to those portions of the tabs which project beyond the ends 10 and 12 of the collar 8 when the tabs 55 are not folded back as explained below.

55 60 Preferably, each of the inner end portions of the respective tabs 16 and 18 is secured to the underside of the collar 8 by means of stitching such as that designated by the numerals 24 and 26. As shown in FIGURE 5, the inner end 20 of the tab 16 is preferably folded over prior to the stitching.

65 70 In accordance with conventional practice, the collar 8 comprises at least two plies of fabric 7 and 9 which are joined together by the stitches extending parallel to the finished edges thereof. The ply 7 forms the outside ply

3

of the collar 8 while the ply 9 forms the inside or underside of collar 8. The collar is closed by a conventional button 11 as shown in FIGURE 1. Preferably, also in accordance with conventional practice, a stiffening element or material is interposed between the plies, and if desired, a "stay" of conventional elongated pointed tip design may extend radially inward from the base of the edges 10 and 12. The multi-ply construction, and the use of "stays," are well known in the art and thus form no part of the instant invention. It is to be understood, however, that the tab means provided by the instant invention allows for the utilization of conventional collar construction with or without stays, with or without a stiffening element, and with or without any other conventional expedients.

If reference is again made to FIGURE 3, it will be noted that the inner end portion of the first tab 16 in addition to being secured to the underside of the collar 8 carries a female snap-fastening element 30. Similarly, the inner end portion of the second tab 18 secured to the underside of the collar 8 adjacent the opposite end thereof carries a male snap-fastener element generally designated by the numeral 32. The stitching 24 and 26 securing the ends of the tab in place, in accordance with the preferred embodiment of the invention, passes only through the inner ply 9 of the multi-ply collar 8 so that, as shown in FIGURE 1, the stitching does not appear on the front face or outer ply 7 of the collar. Similarly, the fastening elements 30 and 32 which are preferably of conventional design, incorporating rivet-type interlocking components, are secured in position by placing one of the interlocking components between the plies of the multi-ply construction and the other of the interlocking components, on the remote or outside face of the tab to which the component is attached, as shown in FIGURE 6.

Regardless of the manner in which the fastener elements are secured in place, the inner end portion of one of the tabs is provided with a female coupling element thereon, and the inner end portion of the other tab is provided with a male coupling element thereon. Each of the tabs in addition to carrying a snap-fastening element on its inner end portion, also carries a snap-fastening element on the outer end portion thereof which overlaps the outer end portion of the other tab. The tab 16, as shown, is provided with a female snap-fastening element 30 in the inner end thereof and a male snap-fastening element 34 on the outer end thereof. The tab 18, on the other hand, is provided with a male snap-fastening element 32 on the inner end portion thereof, and with a female snap-fastening element 36 on the outer end portion thereof. The snap-fastening elements 34 and 36 are of conventional design, like the snap-fastening elements 30 and 32. They are coupled on the tabs by passing the cooperating rivet-type interlocking components through each of the tabs with the cooperating fastener components disposed in facing relation to one another whereby the outer ends of the tabs 16 and 18 can be detachably coupled together as shown in FIGURE 3.

FIGURE 6 (a) presents the disposition of the interlocking cooperating components 30(a) and 30(b) of female fastener element 30, whereas FIGURE 6(b) presents the disposition of the interlocking cooperating components 32(a) and 32(b) of male fastener element 32. The fastener elements 30 and 32, like the fastener elements 34 and 36, are of conventional design and can be of the form shown in United States Patents Nos. 1,146,696, 2,053,820, or 2,106,728, or of other suitable construction.

As explained above, when the outer ends of the tabs are detachably coupled together as shown in FIGURES 1 and 3, then they serve to maintain the ends 10 and 12 of the collar, or wing portions adjacent such ends, in the desired position. A necktie such as that shown in phantom and designated by the numeral 50 in FIGURE 1 would, in normal practice, be provided with a knot which passes over the tabs 16 and 18 thereby hiding the same from view.

4

Supposing, for the instant, that it is desired to wear the collar open, then the tabs 16 and 18 would be folded back upon themselves. Consider FIGURE 5 and tab 18 initially. The outer end portion of this tab, as shown in FIGURE 5, is folded back upon the inner end portion thereof. The outer end portion, being provided with a female coupling 36 as explained above, can be detachably coupled to the inner end portion by pressing the female coupling element 36 into coupling engagement with the male coupling element 32 carried at the inner end portion of the tab 18. Similarly, the inner end portion of the tab 16 carries a female coupling element and the outer end portion of this tab carries a male coupling element. The tab 16, as opposed to being folded merely in half, is doubled over upon itself as shown in FIGURE 5 so that the male snap fastening element 34 is in position to detachably engage the female snap-fastening element 30.

By providing snap-fastening elements at the inner and outer ends of the tabs, which snap-fastening elements have a different "sex," the snap-fastener elements carried on the overlapping outer end portions of the tabs cooperate, as explained, when the shirt collar is worn closed to detachably connect the tabs together to maintain the end of the shirt collar in closed position. At the same time, the snap-fastener elements on the inner and outer end portions on each of the tabs cooperates, when the shirt collar is worn open, to detachably secure the outer end portions of each of the tabs to the respective inner end portions with the outer end portions folded over the inner end portions behind the underside of the shirt collar. When the collar is worn closed, the tabs are hidden from view by virtue of the necktie knot. When the collar is worn open, the tabs are hidden from view since they are folded back beneath the turned-down collar 8.

Preferably, the tabs 16 and 18 are of the same length whereby the overlapping portions carrying the cooperating snap-fastening elements detachably connect the tabs together centrally of the necktie-knot receiving opening 14. However, the tabs can be of varying lengths without departing from the scope and spirit of the invention. It is important, notwithstanding this fact, that the tab element which carries the female snap-fastening element at the inner end thereof, have an unattached length which is greater than twice the width of the male snap-fastening element carried at the outer end thereof. If reference is made to FIGURE 3, it will be noted that the unattached length of the tab 16 is designated by the numeral *d*. This length extends from the outside edge of the snap-fastening element 30 to the outside edge of the snap-fastening element 34. As explained, the tab 16 is not merely doubled over, but is folded inwardly upon itself and then folded over, as shown in FIGURE 5, so that the male snap-fastening element 34 mates with the female snap-fastening element 30. To achieve this necessary folding over, the unattached length designated by the numeral *d* must be greater than twice the greatest width, or twice the width of the widest part of the outer snap-fastening element 34.

While I have described hereinabove the preferred construction of the improved shirt collar provided by the present invention, and the manner in which the tabs thereof can be utilized to advantage, it is to be understood that various modifications can be made to the construction shown, in addition to those specifically suggested, without departing from the scope and spirit of the invention. Accordingly, what is claimed is:

On a turn-down shirt collar formed of an inner ply and an outer ply and having, in closed position, two ends disposed in spaced relation defining a necktie knot receiving area, the improvement comprising first and second tabs having overlapping outer end portions projecting beyond each of said ends of said collar, the inner end portion of said first tab being secured to the underside of said inner ply adjacent one of said ends by interlocking cooperating components of a female snap-fastener element and by stitching normally hidden from view by said outer ply,

the inner end portion of said second tab being secured to the underside of said inner ply adjacent the other of said ends by interlocking cooperating components of a male snap-fastener element and by stitching normally hidden from view by said outer ply, and the overlapping outer end portions of said first and second tabs carrying respectively male and female snap-fastener elements, said snap-fastener elements carried on said overlapping outer end portions of said tabs cooperating when said shirt collar is worn closed to detachably connect said tabs together to maintain said ends of said collar in closed position, said first tab having an unattached length between the outer extremity of said male snap fastener element carried by said first tab and said collar greater than at least twice the width of said last-mentioned male snap-fastener element whereby, when said shirt collar is worn open, said

5 snap-fastener elements on the inner and outer end portions of each of said tabs cooperate to detachably secure said outer end portions to said inner end portions with said outer end portions folded-over said inner end portions respectively behind said underside of said shirt collar.
